UNITED STATES PATENT OFFICE

HAROLD M. NEWTON, OF CLAYTON, MISSOURI, ASSIGNOR TO MIDLAND CREOSOTING COMPANY, OF TOLEDO, OHIO, A CORPORATION OF OHIO

FLOORING

Application filed September 8, 1931. Serial No. 561,655.

This invention relates to flooring or pavement, and with regard to certain more specific features, to a wood or similar block type of flooring or pavement.

5 Among the several objects of the invention may be noted the provision of an improvement in assembling into strips of suitable length blocks of the class described, said blocks being arranged, in one form, to present an end-grain surface for resisting wear; the provision of improved forms of keys and splining tongues fitted to suitably located grooves and adapted to interlock with adjoining grooves in adjacent strips of blocks; 10 the provision of a product of the class described which shall present an even surface after being laid, said product having a desirable degree of flexibility so as to follow accurately the general lay of the surface to 15 which the floor is applied without following local irregularities and without warping; and the provision of a product having the above and other improved characteristics. Other objects will be in part obvious and in 20 part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention,

Fig. 1 is a plan view showing a fragmentary section of laid flooring;

Fig. 2 is a side elevation of Fig. 1;

40 Fig. 3 is an enlarged cross section taken substantially on line 3—3 of Fig. 1;

Fig. 4 is a horizontal section taken substantially on line 4—4 of Fig. 3;

Fig. 5 is an enlarged diagram showing the 5 relationship between a wire key and a block before the key is applied;

Fig. 6 is a view similar to Fig. 5, showing the relationship of parts after the key has been applied;

50 Fig. 7 is a trimetric view illustrating a

modified form of end arrangement of spline and key;

Fig. 8 is a plan view of a modified form of the invention, certain parts being broken away;

55 Fig. 9 is an end view of Fig. 8;

Fig. 10 is a plan view of a fragmentary section of flooring embodying the modified form of block illustrated in Figs. 8 and 9;

Fig. 11 is an enlarged cross section taken 60 substantially on line 11—11 of Fig. 10;

Fig. 12 is a view similar to Fig. 4 but showing a form of the invention wherein a spline tongue and a key are in the same groove;

Fig. 13 is a diagrammatic view showing 65 another modification;

Fig. 14 shows a detail of a modification of Fig. 8; and,

Fig. 15 is a view similar to Fig. 14 showing 70 another modification.

Similar reference characters indicate corresponding parts throughout the several views of the drawings.

Wood blocks, cut to present end grain to wear, when applied individually to a floor or 75 pavement are substantially as uneven as the floor itself. Attempts have been made to provide smoothness by bridging over the hollow spaces in a rough floor or the like by applying to the bottom of the blocks a layer 80 of longitudinally grained wood or the like, tongue-and-grooved to the blocks. Successive strips of blocks thus assembled were keyed and splined by means of grooved, wooden tongues. Some of the disadvantages 85 of this form are the expense and complication of construction involved, and the fact that the longitudinally grained flooring beneath the end grained blocks warps the surface out of shape; and the construction is 90 heavier. Furthermore, it has not been easy to follow the contour of the floor, because of the inflexibility of this form of flooring.

Flat metal tongues are found to be heavy 95 and difficult of placement in the blocks and they are not properly held in place by the blocks.

Dowels placed in through holes are not satisfactory because of the expense of construction and the weakening of the blocks 100

by the through holes necessary for accommodating the dowels. The present invention provides for working the block at a region where the weakening effect is negligible.

The present invention overcomes the above and other difficulties encountered with prior types of this flooring.

Referring now more particularly to Fig. 1, 10 numeral 1 refers to rectangular blocks which are adapted to lie with the end grain vertically disposed, as shown. These blocks are arranged in rows as indicated by numerals 3 and 5, each row being originally made up 15 separately as an organization of blocks constituting a strip.

As shown in Figs. 2 and 3, each row of 20 blocks or strip is provided with longitudinally arranged side grooves 7 having, for example, a width of 14 gage (.083 inch). These 25 grooves are formed while the blocks are aligned side-by-side and turned up-side-down on a flat surface, whereby the subsequent upper floor surface is rendered accurate. The grooves 7 are accurately spaced 30 from the tops of the blocks, as are all of the other grooves herein described. The spacing from the bottom is also substantially accurate but this latter accuracy depends upon the accuracy with which the blocks were originally sawed to length.

Into each groove 7, while the blocks of a 35 given row are aligned and lying side by side, up-side-down on the level surface is forced a length of wire, as illustrated in Figs. 5 and 6. The wire is of larger gage than the groove, for example, in the case of the groove above set out a 9 gage wire (.148 inch) is 40 suitable. The wire being substantially larger than the groove, it is necessary that it be pressed in with some force that it may be driven from the position shown in Fig. 5 to that shown in Fig. 6. The depth of the 45 groove 7 is greater than the diameter of the wire 9, so that the wire sinks below the outer aligned faces 11 of a given row of blocks (Fig. 6). This provides adequate material 50 for subsequent finishing after wire placement.

Because of the springiness of the end grain fiber of the wood, the groove tends to close in over the wire as shown in Fig. 6 at numeral 13, thus positively holding the wire in place 55 and providing a compressive effect around the wire which prevents the blocks from sliding longitudinally thereon. The closing-in effect of the wood around the wire may be enhanced by spraying water or the like on 60 the groove before or after the wire is placed, thus swelling the fibers so that they more readily assume their original set after having been forced apart by the wire. This procedure is however not absolutely necessary.

In the above manner the blocks 1 are juxtaposed in permanent rows or strips or units. It will be seen that the interposition of the wires on each side of a given strip (Fig. 3) results in the strips bridging local depressions in a rough floor such as a concrete floor and at the same time permits of a general bending of the strip in order to follow more general undulations in the floor contour upon which the strips are placed. The last-named effect is not interfered with by means of any sub-flooring attached to the blocks, as was the case in some prior structures above referred to. In short, the wires prevent local bending but permit a general bending of the strips. 70 At the same time the wires 9 have been accurately spaced from the upper surface 14 of the blocks, to cause a smooth surface to be presented upwardly, whether the general surface be flat or undulating. The use of wire, 75 instead of other types of tongues, permits of proper forcing into place of the tongue and the advantageous closing in action of the wood around the groove.

Ordinarily, I have found that it is not 80 necessary to carry the wire 9 beyond the ends of the strips 3, 5, because the friction of the wood against the wires is so great that endwise slippage is substantially prevented. However, if it be preferred, extra lengths 85 15 of wire may be left extending at the ends of the strips, as shown in Fig. 7, to be turned over and to function as endwise clamps.

In order that adjacent strips or rows 3, 5 may be aligned and fastened by splining, 100 I provide in one form of the invention a second set of grooves 17. One of these is to function as a groove to receive a tongue or spline member 19 fastened in an adjacent strip. The tongue member 19 preferably 105 comprises a length of crimped wire having an undulating or wave-shape, the troughs of which are forced into one groove of a given strip 5, and the crests of which extend therefrom and are adapted to be forced into the 110 groove 17 of the adjacent strip 3 when the floor is laid. The relationship between the dimensions of the groove 17 and of the tongue 19 is of the order of that set out for the 115 grooves 7 and wires 9. Thus the fibers of the wood spring in over the troughs and crests of the undulation of the splined wire 19 as shown in Fig. 3, so as to effect a tight splining between the successive strips 3, 5.

It is clear from the above, that each assembled strip carries a blank groove 17 on one side, and a groove 17 on the other side in which is pre-positioned the spline wire 19. Fig. 3 illustrates this point. Fig. 4 shows the arrangement of the splines, numerals 21 referring to the regions at which the wood fibers recover their original position to clamp over the crests and troughs of the crimped wire. Fig. 7 also illustrates how, if desired, the ends of the splines 19 may be shaped to 130

function as end-clamps 23, although this also is not a necessity.

As illustrated in Fig. 12, the same groove which carries the key wire may be cut deeper 5 and caused also to carry the spline wire 19. This method of applying both key and spline wires also permits the wood fibers to clamp around both wires in the manner described. It will be appreciated that a strip embodying 10 this modification will have one groove on each side, the groove on one side having in it a straight wire imbedded deeply and a crimped wire imbedded not so deeply. The groove on the other side will be without a 15 wire. This groove will receive its crimped wire when the adjacent strip is juxtaposed, as when laying a floor or the like.

The last-named modification can also be carried out by imbedding the crimped wire 20 29 deeply in one side of the strip (Fig. 13). The other side has a blank groove 27 with a deeply inset straight wire 31. Then when the strips are laid, the deeply inset crimped wire 29 goes into the opposite groove 27 with 25 the deeply laid straight wire 31.

It will be appreciated that many other forms and arrangements of key and splined members may be thought of which will come within the principles set forth in the present 30 description.

In Figs. 8 to 11, 14 and 15 is shown the application of the invention to a modified form of flooring, known as block inlay flooring. This flooring does not present end grain 35 to wear but comprises square units or like slabs made up of short strips heretofore mechanically held together by separate devices which were no part of the tongue and groove. These units were held together by means of 40 tongues and grooves formed from the strips themselves.

Referring to Fig. 8, there is shown a plurality of boards or strips 33 juxtaposed but not tongued and grooved at the interior edges 45 35. They are merely abutted. At the ends, these boards are grooved as shown at numeral 37 to receive wires 39, substantially in the manner above described. However, in this modification it is well that the wires be not 50 as much oversized with respect to the groove as they were in the first-named modification. The two wires 39 thus frictionally hold the boards 33 together to form a square unit. The wires 39 are also placed deep enough so 55 that a groove is left above them for receiving certain tongue portions next to be described.

Laterally the endwise boards are grooved with the grain as shown at numeral 41 for receiving, substantially in the manner described, crimped wires 43. These crimped wires form extending tongues for alignment purposes when laying the floor, this being illustrated in Fig. 9.

In Fig. 10 is shown how the assemblies of 65 boards are arranged to form flooring. An

assemblage such as indicated by numeral 45 is laid down. Then an assemblage such as indicated by numeral 47 is relatively turned through 90 degrees and the crimped tongues 43 are inserted in the remainder of the groove 37 not occupied by its wire 39. This process is continued, each alternate assemblage being positioned at 90 degrees with respect to the adjacent one, and having its tongue applied to the groove of said adjacent assemblage. 75 The final result is that the entire floor is thoroughly interlocked without the use of any tongue-and-grooved boards in the sense that they have been heretofore known.

Fig. 11 illustrates the appearance of the 80 joint after the floor is laid. It will be seen that Figs. 8 to 11 also illustrate the point which is made in connection with Fig. 13, namely, the use of tongues and keys in juxtaposed grooves, instead of in grooves on different planes.

It is to be understood that crimped wires 43 may be substituted for the straight wires 39 in grooves 37 and grooves 41 left open to receive projecting crests of adjacent crimped 85 wires, as illustrated in Fig. 15. Or, this modification may be effected with an extra straight wire 39 at the base of the groove 37 in which the crimped wire 43 is placed, as 90 illustrated in Fig. 14.

The character of the wire can be made to determine the degree of flexibility in the final strip. For instance, if malleable wire is used, there will be a great flexibility and if a hard Bessemer wire is used the strips will be relatively stiff. Or the diameters may be varied. Thus the degree of flexibility may be better varied by use of metal wire. However, it is to be noticed that the round cross section of 100 the wire may be used, without making the key and spline pieces of metal. For instance, 105 they may be made of fiber or the like.

In view of the above, it will be seen that the several objects of the invention are 110 achieved and other advantageous results attained.

As many changes could be made in carrying out the above constructions without departing from the scope of the invention, it is intended that all matter contained in the 115 above description or shown in the accompanying drawings shall be interpreted as illustrative and not in a limiting sense.

I claim:

1. Flooring comprising units, the units being composed of juxtaposed wood members, aligned grooves in the members and wire in said grooves joining said members, said grooves having widths normally less than the diameter of the wire, the grooves being so arranged with respect to the natural grain of the wood that said wood presents end grain to wear after the flooring is laid. 120

2. Flooring comprising juxtaposed strips, 125 said strips being made up of juxtaposed

blocks, grooves cut edgewise of the strips and across adjoining blocks, key wires in at least some of the grooves and crimped spline wires in at least some of said grooves, said spline wires having troughs in their respective grooves and crests outside of said grooves.

3. Flooring comprising juxtaposed strips, said strips being made up of juxtaposed blocks, grooves cut edgewise of the strips and across adjoining blocks, key wires in at least some of the grooves and crimped spline wires in at least some of said grooves, said spline wires having troughs in their respective grooves and crests outside of said grooves, said grooves being of a width normally less than the diameter of said wires.

4. Flooring comprising units, said units being composed of juxtaposed pieces, grooves in said pieces, spline members in said grooves, said grooves being normally narrower than the spline members therein, said spline members having portions extending from the groove and also portions depressed in the groove to a depth which is greater than the depressed portion of said spline member.

5. Flooring comprising strips, the strips being composed of juxtaposed blocks of wood, the end grains of which are presented vertically with respect to the strips, grooves in the sides of the strips and key wires in the grooves, said key wires having a diameter which is greater than the normal width of said grooves but less than the depth thereof, and crimped spline wires in at least some of the grooves, said spline wires having crests extending from the grooves in which they are located.

6. Flooring comprising strips, the strips being composed of juxtaposed blocks of wood, the end grains of which are presented vertically with respect to the strips, grooves in the sides of the strips and key wires in the grooves, said key wires having a diameter which is greater than the normal width of said grooves but less than the depth thereof, and crimped spline wires in at least some of the grooves, said spline wires having crests extending from the grooves in which they are located, at least some of said spline and key wires being in a single groove before a floor is laid.

7. Flooring comprising strips, the strips being composed of juxtaposed blocks of wood, the end grains of which are presented vertically with respect to the strips, grooves in the sides of the strips and key wires in the grooves, said key wires having a diameter which is greater than the normal width of said grooves but less than the depth thereof, and crimped spline wires in at least some of the grooves, said spline wires having crests extending from the grooves in which they are located, at least some of said spline and key wires being in a single groove.

8. Flooring units comprising juxtaposed

boards, grooves in said boards endwise thereof, grooves in the lateral edges of the outermost ones of said boards, key wires tightly held in the endwise grooves and crimped spline wires in the lateral grooves, the crimps of the spline wires extending from their respective grooves at certain points.

9. Flooring units comprising juxtaposed boards, grooves in said boards endwise thereof, grooves in the lateral edges of the outermost ones of said boards, key wires tightly held in the endwise grooves and crimped spline wires in the lateral grooves, the crimps of the spline wires extending from their respective grooves at certain points, the units of the flooring being laid so that said spline wires extended to a juxtaposed groove which holds a key wire on the adjacent unit.

10. Flooring units comprising juxtaposed boards, grooves in said boards and wires thereof, grooves in the lateral edges of the outermost ends of said boards, and crimped spline wires in the end wire grooves.

11. Flooring units comprising juxtaposed boards, grooves in said boards and wires thereof, grooves in the lateral edges of the outermost ends of said boards, crimped spline wires in the end wire grooves and key wires in said endwise grooves below the crimped wire.

In testimony whereof, I have signed my name to this specification this 5th day of September, 1931.

HAROLD M. NEWTON.
